UNITED STATES PATENT OFFICE.

JOHN J. FLEMING, OF VINELAND, NEW JERSEY.

METHOD AND APPARATUS FOR MAKING SASH-WEIGHT MOLDS.

Application filed August 27, 1925. Serial No. 52,721.

My invention relates to a method and apparatus for making sash weight molds.

The usual method of making a mold for sash weights is to ram sand around horizontal sash weight patterns arranged in horizontal rows one above the other. This is done by first ramming the sand around the bottom row of patterns, then placing another row above and ramming sand around that row and so on until five or six rows have been rammed. As each succeeding upper row of patterns is rammed with sand, the sand around the bottom row is compressed more and more. This compression forces the sand from the under side of each pattern in the bottom row and leaves a space which makes the impression larger than the pattern and molds a sash weight which is too heavy. This enlarging of the impressions due to compressing the sand, is greatest at the bottom row of patterns and least at the second row from the top. This causes weights to be produced of varying weights. Weights, which are too heavy, are highly objectionable because they overbalance the window sash and tend to keep it open.

The objects of my invention are to provide a method whereby sash weights of uniform weight may be produced in large quantities and at a low cost and apparatus for carrying the method into effect.

These objects, and other advantageous ends which will be described hereinafter, I attain in the following manner, reference being had to the accompanying drawings in which

Figure 1 is a sectional perspective view through a mold made in accordance with my invention;

Figure 2 a front elevation of a sash weight molded in the mold shown in Figure 1;

Figure 3 a side elevation partly in section of the sash weight shown in Figure 2;

Figure 4 a side elevation of sash weight patterns mounted on a support;

Figure 5 a central section through a flask having the pattern mounted therein;

Figure 6 a view similar to Figure 5 showing the flask rammed with sand;

Figure 7 a view similar to Figure 6 showing a gate plate pressed in the sand to form gates leading to the patterns;

Figure 8 a plan view of the gate plate shown in Figure 7, and

Figure 9 a section on line 9—9 of Figure 8.

Referring to the drawings, 1 indicates a flask preferably of cast metal having an open top 2 and a bottom 3 provided with 60 openings 4 to receive sash weight patterns 5. The patterns are suitably mounted on a pattern support 6. The upper ends 7 of the patterns are reduced to form a part of the gates in the sand for the metal when 65 poured into the molds. The patterns extend through openings 4 into the flask and pattern support 6 abuts the bottom of the flask as shown in Figure 5. The height of the upper ends 7 is such that they are even 70 with the upper edge of the flask. A flask extension 8, of rectangular cross section, rests on the edges of the flask to hold a sufficient quantity of sand 9 for ramming purposes. A gate-forming plate 10 has 75 ridges 11 and perforations 12 passing through the ridges. These perforations fit over the upper ends 7 of the patterns when the gate plate is pressed into the rammed sand to form gates for the metal to flow into 80 the molds.

The method for making the sash weight molds is as follows:

The pattern support 6 and patterns 5 are placed on a sand bed as shown in Figure 85 4 and the flask is placed on support 6 with the patterns 5 extending through openings 4 into the flask as shown in Figure 5. Extension 8 is then placed on the upper edges of the flask and the flask and extension 90 filled with sand 9. The sand is then rammed or forced between the patterns to a level even with the upper ends of the patterns as shown in Figure 6, after which the extension is removed and gate plate 10 95 placed on the sand with its perforations 12 fitting the upper ends 7 of the patterns. The plate is pressed into the sand as shown in Figure 7 and then removed. The ridges 11 in the gate plate form gates 13, as shown in Figure 1, leading to the upper ends 7 of the patterns. The patterns are then removed through the openings 4 in the bottom of the flask. The molds 14 left in the sand by the patterns are of the same size as 105 the patterns and uniform therewith. This insures molding all sash weights of correct and uniform weight. The lower end of molds 14 are then plugged by suitable cores 15. The molds are then ready for pouring. The 110

metal poured will flow into the gates 13 and down into the molds 14. After the weights are molded they will be as shown at 16 in Figures 2 and 3. The upper end 5 17, to which the sash cord is attached when connected to a window sash, is formed by the cores 15.

It will be seen that sash weights, molded as above described, will be of accurate and 10 uniform weight and that the weights may be produced in large quantities and at low cost.

While I have described my invention as taking a particular form, it will be understood that the various parts may be changed without departing from the spirit thereof, and hence I do not limit myself to the precise construction set forth, but consider that I am at liberty to make such changes and 20 alterations as fairly come within the scope of the appended claims.

Having thus described my invention, what I claim as new and desire to secure by Letters Patent is:—

- 25 1. A method of making sash weight molds consisting in inserting patterns into and through one end of a flask, filling the flask with sand through its opposite end to a level above the patterns, ramming the sand even with the upper ends of the patterns, compressing the sand to form gates adjacent the upper free ends of the pattern, and removing the pattern through the first mentioned end of the flask.
- 30 2. Apparatus for making sash weight molds including a flask having an open top and a bottom provided with a plurality of openings, and patterns extending through the openings into the flask, thereby permitting sand to be rammed between the patterns through the top of the flask.
- 35 3. Apparatus for making sash weight molds including a flask having an open top and a bottom having a plurality of open-

ings; a pattern support adapted to abut the bottom of the flask, and patterns mounted on the support adapted to extend through the openings in the bottom into the flask, thereby permitting sand to be rammed between the patterns through the top of the flask. 45 50

4. Apparatus for making sash weight molds including a flask open at its upper end and having a bottom provided with a plurality of openings; a pattern support adapted to abut the bottom of the flask; patterns mounted on the support and extending through the openings in the bottom into the flask, and an extension on the upper end of the flask, thereby permitting the sand filling the flask and the extension to be rammed between the patterns through the upper end of the flask. 55 60

5. Apparatus for making sash weight molds including a flask open at its upper end; a pattern support adapted to abut the bottom of the flask; patterns mounted on the support and extending through the bottom into the flask; an extension on the upper end of the flask for holding the sand to be rammed between the patterns, and a perforated gate plate fitting over the upper ends of the patterns and adapted to press the sand to form gates leading to the patterns. 65 70

6. Apparatus for making sash weight molds including a flask having openings in its bottom; a pattern support adapted to abut the bottom; patterns mounted on the support and adapted to extend through the openings into the flask; an extension on the flask above the upper ends of the patterns 75 80 for holding sand to be rammed to a level even with the upper ends of the patterns, and a perforated gate plate adapted to fit over the upper ends of the patterns and press the sand to form gates leading to the patterns. 85

In testimony whereof I have signed my name to this specification.

JOHN J. FLEMING.
